UNITED STATES PATENT OFFICE.

CHARLES A. WENDT, OF MILWAUKEE, WISCONSIN.

RETURN-CHUTE RECOVERY TRAY.

1,406,593.

Specification of Letters Patent. Patented Feb. 14, 1922.

Application filed April 15, 1921. Serial No. 461,670.

To all whom it may concern:

Be it known that I, CHARLES A. WENDT, a citizen of the United States, and resident of Milwaukee, in the county of Milwaukee and State of Wisconsin, have invented certain new and useful Improvements in Return-Chute Recovery Trays; and I do hereby declare that the following is a full, clear, and exact description thereof.

10 This invention relates to pocket billiard tables, and more particularly to means for receiving the balls delivered from the pockets.

The invention comprises the customary inclined chutes communicating with the 15 pockets and terminating at a point adjacent one of the partitions of the table.

The general object of the invention is to provide means connected with the chute for removably supporting a tray or receptacle in which the balls are received as they 20 roll from the pockets, and which may be easily removed for the purpose of emptying the balls on to the table to be set for the next game.

25 With the above objects in view, the invention comprises certain structural details which will be herein described in connection with the accompanying drawing, in which:

Figure 1 is a vertical longitudinal sectional view through one end of the table with my invention applied thereto, and

Figure 2 is a horizontal sectional view.

Referring in detail to the drawings, the numeral 1 designates the end of a table, and 35 2 and 3 indicate chutes which lead from

the pockets to a common discharge mouth 4, which communicates with an opening 5 in the end of the table. A cushion 6 of rubber or the like is provided at the mouth of the chute, where the inclined portions of the 40 chute merge into the horizontal portion. A bracket 7 is secured to the lower side of the end 1 by means of screws 8 or the like. This bracket is formed with a central opening 9 with downwardly converging sides which are 45 preferably provided with a metallic lining 10 in order to reinforce the same.

It will be readily understood that a tray or receptacle of the proper shape to fit within the opening 9 may be used for receiving the balls, as they are delivered from the brackets, and when the game has been completed the tray may be readily removed to discharge the balls on to the table.

I claim as my invention:

In combination with a pocket billiard table, a plurality of chutes leading from the pockets thereof and having a common discharge mouth, a pocket projecting from one end of the table, and a cushion on the bracket 55 extending across the discharge mouth against which the balls strike as they roll down the chutes and a socket in said bracket for removably receiving a tray.

In testimony that I claim the foregoing 60 I have hereunto set my hand at Milwaukee, 65 in the county of Milwaukee and State of Wisconsin.

CHARLES A. WENDT.
